UNITED STATES PATENT OFFICE.

FREDERICK MOENCH, OF RUSHVILLE, ILLINOIS.

SPARK-PLUG.

1,172,159.

Specification of Letters Patent. Patented Feb. 15, 1916.

Application filed June 23, 1915. Serial No. 35,780.

To all whom it may concern:

Be it known that I, FREDERICK MOENCH, a citizen of the United States, and a resident of Rushville, in the county of Schuyler and State of Illinois, have invented a certain new and useful Improvement in Spark-Plugs, of which the following is a specification.

My present invention relates to spark plugs, my object being to provide a substantially integral structure which will be strong and durable in use, neat and simple in appearance, and which may be more readily and economically manufactured than the spark plugs now in use.

With these objects in mind my invention resides in the details of construction to be now described with reference to the accompanying drawing which forms a part of this specification, and in which the figure is a central longitudinal section through my improved insulator.

Referring now to this figure, it will be seen that I provide a hollow nut A, through the bore of which the insulator B extends, said nut forming a single piece base in view of the particular connections proposed by this invention between the nut and the insulator just mentioned, and which will be hereinafter described, such connections doing away with the use of the usual threaded gasket for connecting the insulator to the base. It will thus be seen that but a single set of threads A' are necessary upon the base constituted by the nut A, the latter including also a polygonal portion A² by means of which it may be quickly threaded into, and removed from, the proper cylinder opening.

The connections just mentioned between the base A and the insulator B, are formed at C and C', at the respectively opposite ends of the nut A, and from aluminum solder according to a process which forms the subject matter of a separate application, such connections permanently uniting the porcelain with the base or nut A and acting as reinforcements for the porcelain B.

It will be noted that the inner end of the porcelain B, as indicated at B', projects beyond the inner end of the nut A, the inner end of whose bore is completely closed, and that this inner end of the porcelain B is further reinforced by a similar soldered connec-

tion D uniting therewith the inner end of the central electrode E, the opposite end of which has a soldered aluminum cap E' seated upon the outer end of the porcelain B. The other or bent electrode D' which is secured into the body or nut A, has one end thereof bent into contiguous relation to the inner end of the central electrode E, and these ends are preferably provided with platinum tips D² as plainly shown. Thus the aluminum connections at C, C', D and E' serve to permanently and rigidly unite the several parts of my improved spark plug, strengthening the same, increasing its durability and effectiveness, and permitting of its manufacture in a more ready and economical manner than is possible with the spark plugs now in general use.

I claim:

1. A spark plug consisting of an insulator, a threaded base through which the insulator extends, an electrode extending through the insulator, and soldered metallic connections between the said electrode and the insulator and between the insulator and the said base, and permanently uniting these parts to form a substantially single piece plug, said soldered connections being located at the inner ends of the insulator and nut whereby to permanently close the spaces between the same and the electrode. 85

2. A spark plug comprising a nut forming a single piece base, an insulator extending through the said nut, and permanent soldered connections between the insulator and the nut located at the opposite ends of the latter and around the insulator whereby to permanently close the space between them. 90

3. A spark plug comprising a nut forming a single piece base, having a bore and a single series of threads, an insulator extending through the bore of the said nut and projecting at its inner end beyond the inner end of the nut, soldered metallic connections between the said insulator and the said nut, located at the respectively opposite ends of the nut and entirely closing the ends of its bore, and electrodes carried by the said insulator and the said nut. 100

FREDERICK MOENCH.
